UNITED STATES PATENT OFFICE.

FRANK WOJCIUCH, OF CLEVELAND, OHIO.

DESIGN FOR A PICTURE-FRAME.

51,034.

Specification for Design.

Patented July 10, 1917.

Application filed April 23, 1917. Serial No. 164,065. Term of patent 7 years.

To all whom it may concern:

Be it known that I, FRANK Wojciuch, a subject of the Emperor of Austria, residing at Cleveland, in the State of Ohio, have invented a new, original, and ornamental Design for Picture-Frames, of which the following is a specification, reference being had to the accompanying drawing, forming part thereof.

Fig. 2 is a cross section through a part of the frame.

I claim:

The ornamental design for a picture frame as shown.

In testimony whereof I affix my signature.

FRANK WOJCIUCH.
